HARNESS CORD SHEAVE MECHANISM FOR LOOMS

Oscar V. Payne, Leicester, Mass., assignor to Crompton & Knowles Loom Works, Worcester, Mass., a corporation of Massachusetts

Application June 3, 1944, Serial No. 538,599

9 Claims. (Cl. 139—55)

This invention relates to improvements in harness mechanisms for looms and it is the general object of the invention to provide an improved harness cord sheave mechanism which permits the use of longer hubs on the sheaves than have been used heretofore.

The harness frames of looms are usually arranged side by side in close relationship and are raised and lowered by mechanism including jacks or levers which are also close together. Harness cords extend from the jacks over sheaves to the harness frames, and the sheaves are usually as closely related as are the jacks and frames. It has been customary in the past to place all of the sheaves for one end of the group of harness frames on a single shaft with the result that the sheave hubs have been too short to withstand the wearing incident to their constant oscillation. It is an important object of my present invention to provide two sets of sheaves, each having its own supporting shaft and each sheave having a hub which is approximately twice the width of the sheave, thereby affording a considerable increase in the wearing surface of the hub.

In arranging the sheaves between the loom arches it is desirable that as little space be wasted as possible so that the loom will have capacity for a large number of harness frames. It is another object of my present invention to arrange the hub and sheave relationship in such a manner that a large part of the available space between the loom arches can be utilized for sheaves. This result will be accomplished by using a hub the greater part of which lies on one side of the rim of the hub and arranging all of the sheaves in one set with the long parts of their hubs facing in one direction such as forwardly, and arranging all the sheaves of the other set with the long parts of their hubs facing in the opposite direction, such as rearwardly. By this arrangement the rims of one set are staggered with respect to the rims of the other set to provide proper clearance for the harness cords, and no space is wasted between the arches. I find that these results can be conveniently accomplished by having that part of the hub of one side of the plane of the rim three times as long as the other part of the hub lying on the opposite side of the plane.

When two sets of sheaves are used for one end of the group or plurality of harness frames it is desirable that they be located as closely together as possible so that the points of attachment between the harness cords and the harness frames may be near enough to the ends of the harness

frames to establish proper balance when the harness frames are raised and lowered. In order to accomplish this result it is another object of my invention to stagger the sheave rims of one set with respect to the rims of the other set and locate the supporting shafts in such positions that the sheaves of one set overlap, or enter the spaces between, the sheaves of the other set. By this arrangement the distance between the supporting shafts may be substantially less than the diameter of a sheave and the points of connection between the harness frames and the cords of the two sets may be close together.

It is another object of my invention to provide an improved harness cord sheave the hub and rim of which are so related as to make possible the attainment of the foregoing advantages.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of the upper part of a loom showing harness mechanism with my invention applied thereto,

Fig. 2 is a diagrammatic plan view looking in the direction of arrow 2, Fig. 1, showing the staggered relationship of the sheave rims and also showing the relation between the plane of the sheave rims and the ends of their hubs,

Fig. 3 is a view similar to the upper part of Fig. 2 but showing the details of the construction involved, parts being in section, and some parts omitted in the lower part of the figure,

Fig. 4 is a vertical section on line 4—4 of Fig. 3, certain parts of the sheaves being broken away to show the structure behind them, and

Fig. 5 is a vertical section on line 5—5, Fig. 4, looking toward the left.

Referring particularly to Fig. 1, I have shown a loom frame 10 across the upper part of which extend front and back arches 11 and 12, respectively. The arches may support a harness lifting mechanism K including harness jacks or levers 13 and 14, which may be part of a dobby or Knowles head or other convenient harness lifting mechanism. The jacks or levers rock back and forth in a right and left hand direction as viewed in Fig. 1 during loom operation, and it is to be understood that there will be a number of these jacks some of which will occupy the position of jack 13 and others the position of jack 14 in Fig. 1. The order of movement of these jacks

during successive picks of the loom determine the pattern of the fabric being woven.

The loom is provided with a group or plurality of harness frames two of which are shown in Fig. 1. The front harness frame 15 is shown in down position and corresponds to the jack 13, while the harness frame 16 is in up position behind frame 15 and corresponds to jack 14. There will ordinarily be as many harness frames as there are jacks and some of the frames will be in low position while others will be in high position when the warp shed is wide open for the flight of the shuttle.

The jacks are connected to the harness frames by a system of cords designated generally at C, each jack having a connector for two harness cords which run to the corresponding harness frame. Thus, in Fig. 1 connector 18 attached to jack 13 is connected to cords 19 and 20 leading to the front harness frame 15, while the jack 14 is associated with a connector 21 attached by cords 22 and 23 leading to harness frame 16. In the past it has been customary to train the cords 19 and 22 around a set of sheaves all oscillating on a single shaft, and in similar manner the cords 20 and 23 have been trained around another set of sheaves on a single shaft. By such an arrangement, however, the space assignable to each sheave along its shaft will be no longer than the width of a sheave rim or harness frame, and this relationship leads to undue wear of the sheaves when the harness frames are operating with heavy warps. It is an important feature of my invention to provide means for reducing this wear of the sheaves.

The matter thus far described is of common construction and of itself forms no part of my present invention.

In carrying my invention into effect I provide two pairs of sets of sheaves, one pair for each end of the loom, and mount each set on a shaft extending between the arches. These pairs of sets, R and L for the right and left end of the loom, respectively, are alike and a detailed description of one of them such as pair L will suffice for both.

Rear arch 12, see Figs. 3, 4 and 5, is provided with a block 25 having a vertical wall 26 which fits between the top and bottom flanges 27 and 28 of the arch and is held against the vertical web 29 of the arch by means of a bolt 30. Extending forwardly from the ends of the wall 26 are right and left vertically extending wings 32 and 33, respectively, each having a lateral web 34 extending away from the center of the block. Each web 34 is provided with a pair of vertical walls which project forwardly. As shown in Figs. 3 and 4 the outer wall of each pair is designated at 35, while the inner wall of each pair is shown at 36. Each pair of walls defines a vertically extending slot 37 which may if desired be machined to provide smooth interior guide surfaces.

The walls 35 and 36 have their rear edges notched at 38 to receive the top and bottom flanges 27 and 28, respectively of arch 12, and each wall has an extension 39 projecting beyond each notch. The extensions at the tops of walls 35 and 36 are provided with upwardly facing concave pockets 40, see Figs. 3 and 5, which are concentric about an axis substantially parallel to the horizontal part of the loom arches. Resting in each pair of pockets is a cylindrical bearing 41 extending substantially parallel to the arches. An upright bolt 42 passes through each bearing 41 and has a wing nut 43 tapped on the upper end thereof the lower surface of which is con-

cave as at 44 to fit around the upper surface of the cylindrical bearing 41. The lower end of each bolt has a head 45 thereon located in the corresponding slot 37 but too large to turn therein, see 5 the lower right hand part of Fig. 3. For the purpose of illustrating the relation between heads 45 and their slots 37, the wing nuts 43 and bearings 41 have been omitted from the bottom of Fig. 3. Arch 11 is provided with a block 46 similar to 10 and in front of block 25, except that it is reversed, as will be understood from the bottom of Fig. 3.

Extending between blocks 25 and 46 are two parallel horizontal sheaves supporting shafts 50 and 51 the ends of which extend into guide slots 15 37 and are held in adjusted vertical position by the heads 45 of bolts 42. These shafts support sets 52 and 53 of harness cord sheaves, respectively, and each set comprises a plurality of similar sheaves 54 made as shown more particularly in Figs. 2 and 5.

Each sheave has a rim 55 and a hub 56 the greater part of which is displaced on one side of its rim. This relationship is shown diagrammatically in Fig. 2 wherein the heavy horizontal lines 60 represent the planes of the rims of the sheaves in set 52 and the long and short parts of the hub 56 are designated at 61 and 62, respectively. The long part 61 is approximately three times the length of the short part 62. In similar manner the heavy horizontal lines 65 represent the planes of the rims of the set 53. The rims 55 have cord receiving grooves 57 which may be semi-circular in cross section, as seen in Fig. 5, and the plane of each rim may be considered as 30 extending centrally through its groove 57 and perpendicular to its axis.

As shown clearly in Fig. 2 the sheaves of the set 52 are all arranged with the long parts 61 of their hubs extending forwardly while the sheaves of 40 the other set 53 have the long parts 61 of their hubs extending rearwardly. Because of the relationship between the short and long parts of the hubs the reversal of the hubs of one set of sheaves with respect to the hubs of the other set produces 45 a lateral offset or staggering of the rims of each set relatively to the rims of the other set, and the rims of each set align with the long parts 61 of the hubs of the other set, see Fig. 3. It will also be seen from Fig. 2 that the space available 50 between the walls 35 and 36 of blocks 25 and 46, represented by the top and bottom lines I and II, is fully occupied by the sheave hubs except for washers 67.

In Fig. 2 I have shown in full size the relationship 55 between the hub parts 61 and 62 relatively to the plane of the rims as it would exist on a so-called $\frac{1}{16}$ Knowles head in which the hub 56 is 1" long and the long part thereof is $\frac{3}{4}$ " long. I am not limited, however, to this particular size, inasmuch as the invention is applicable to other gauges of harness mechanism so long as the short part 61, represented at a, is approximately one-third the length of the long part 61 represented by 3 $\frac{1}{2}$ in Fig. 2.

Another feature of my invention relates to the 60 location of the rims of one set with respect to the rims of the corresponding set. This relationship is shown more particularly in Figs. 2, 3 and 4, where it will be noted that because of reversed 65 positions of the hubs of the two sets, and also due to the fact that the rims can be much narrower than the hubs, there are spaces between the rims of each sheave into which the rims of the other sheaves can project. Thus, as shown in Fig. 3, the left hand parts of the rims of set 52 extend

into the spaces 70 aligned with long hub parts 61 and located between the right hand parts of the rims of set 53. This overlapping of the rims makes it possible to locate the shafts 50 and 51 close enough together so that the cords 19 and 22 can be attached to their respective harness frames near the left ends of the latter to insure correct balance of the frames, and nearer together than would be possible if the shafts were spaced by a distance greater than the diameter of a sheave.

The rims of each set of sheaves clear the hubs of the other set and also, as will be apparent from Fig. 4, there is sufficient clearance so that either set may be moved to a position higher than the other set without interference on the part of the hubs and rims of the two sets. In this connection it is desirable that the set of sheaves nearer the harness mechanism K be at a somewhat lower level than the other set, although this is not a necessary relationship inasmuch as there is sufficient clearance for the cords if they are all kept in the usual position.

While I have specifically shown and described the details of the group L of sheave sets at the left end of the loom, yet it is to be understood that the group R is of similar construction and is possessed of all the advantages set forth in connection with the group L. The winged nuts afford means for raising and lowering the shafts 50 and 51 for the purpose of locating the harness frames properly in the loom and each shaft is guided by two of the slots 37. By providing the walls 35 and 36 with the notches 38 I am able to locate the bolts 42 very close to the arches. The tops of the walls 35 and 36 overhang the upper part of the arch flange 27 as will be apparent in Fig. 5, thereby affording proper bearing surface between the pockets 40 and the bearings 41. The bottoms of walls 35 and 36 are also provided with pockets 40 so that the blocks can be inverted.

From the foregoing it will be seen that I have provided a simple form of harness sheave arrangement wherein the hubs of the sheaves extend unequal distances on opposite sides of the planes of the rims. This relationship permits a reversal of the hubs of one set with respect to those of the other set while at the same time permitting maximum use of the space between the arches. The advantages of this feature of my invention are best obtained when the short part 61 of the hub is one-third the length of the long part 62. It will also be seen that since the rims of one set are staggered with respect to the rims of the other set the shafts 50 and 51 may be placed so as to effect an overlapping of the rims of the two sets, thereby permitting attachment of the cords to their respective harness frames at points closer together than would be possible without the overlapping of the rims. The harness frames are therefore substantially in balance whether they be connected to cords trained over one or the other of the sets of sheaves. It will also be seen that the walls 35 and 36 extend above and below the flanges of the arches and are provided with overhanging parts in which the pockets 40 are located. The bottoms of the walls are formed similarly to their upper ends and it is for this reason that the blocks 25 and 46 can be inverted.

Having thus described my invention it will be seen that changes and modifications may be made therein by those skilled in the art without departing from the spirit and scope of the invention and I do not wish to be limited to the details herein disclosed, but what I claim is:

1. In harness cord sheave mechanism for a loom, a pair of horizontal parallel shafts, a set of sheaves on each shaft, said sheaves all being similar and each having a cord engaging rim and a hub extending unequal distances on opposite sides of the rim, all the sheaves on one of said shafts having their hubs disposed in the same direction and all the sheaves on the other shaft having their hubs disposed in the opposite direction, and said hubs being so related to the rims as to cause the rims of one set of sheaves to be staggered laterally with respect to the rims of the other set of sheaves.

2. In harness mechanism for a loom, a pair of shafts, a set of harness sheaves on each shaft, the sheaves being similar and each having a rim and a hub having a long part on one side of the corresponding rim, the long part of the hubs of one set all being on the same side of their corresponding rims and the long part of the hubs of the other set all being on the opposite side of their corresponding rims, and the rims of each set being aligned with the long parts of the hubs of the other set and staggered laterally with respect to the rims of the other set.

3. In a loom harness mechanism having two parallel shafts each having a set of harness cord sheaves thereon, all of said sheaves being similar and each sheave having a hub of given length and a cord receiving rim the plane of which is perpendicular to the axis of the hub and passes centrally through the rim and cuts said axis at a point spaced from one end of the hub by a distance equal to one quarter of said given length of the hub, the hubs of the sheaves on each of said shafts being similarly placed with respect to their rims, and the hubs of the sheaves on one shaft being reversed with respect to the hubs of the sheaves on the other shaft so that the rims of one set of sheaves are staggered laterally with respect to the rims of the other set of sheaves.

4. In a loom harness mechanism having two parallel shafts extending between front and back arches, a set of harness cord sheaves on each shaft, said sheaves all being similar and each sheave having a hub and a cord receiving rim the plane of which passing centrally through the rim and perpendicular to the axis of the hub passes between two parts of the hub one of which is three times as long as the other part, each sheave on one of said shafts having the long part of the hub thereof facing the front arch and each sheave on the other shaft having the long part of the hub thereof facing the rear arch, and the rims of one set of sheaves aligning with the long part of the hubs of the other set, whereby the rims of one set of sheaves are staggered laterally relatively to the rims of the other set of sheaves.

5. In harness mechanism for a loom having a pair of arches and a plurality of harness frames, two sets of similar harness sheaves turning about two parallel axes spaced apart a distance less than the diameter of a sheave, and hubs on the sheaves of each set spacing the sheaves laterally in such relation that the sheaves of each set enter spaces between the sheaves of the other set.

6. In harness mechanism for a loom, two sets of similar harness sheaves turning about two parallel axes spaced apart a distance less than the diameter of a sheave, and hubs on the sheaves of each set spacing the sheaves laterally and staggering the sheaves of each set laterally with respect to the sheaves of the other set so that the

sheaves of each set overlap and extend between the sheaves of the other set.

7. In harness mechanism for a loom having a pair of arches and a plurality of harness frames, a pair of shafts extending between the arches, a set of harness sheaves on each shaft, the sheaves being similar and each having a rim and a hub, the hubs of each set separating the rims of the corresponding set by spaces, and the rims of each set extending into the spaces between the rims of the other set.

8. In harness mechanism for a loom having a pair of arches and a plurality of harness frames each having a harness cord, a pair of shafts extending between said arches, a set of harness cord sheaves on each shaft, each sheave having a rim for a harness cord and a bearing hub, the rims of the sheaves on one shaft being staggered laterally with respect to the rims of the sheaves on the other shaft, and means on the arches sup-

porting said shafts a distance apart less than the diameter of a sheave, whereby the rims of one set of sheaves overlap the rims of the other set of sheaves, each set having rims located between rims of the other set.

9. In harness mechanism for a loom, a pair of shafts, a set of harness sheaves on each shaft, the sheaves being similar and each having a rim and a hub having a long part on one side of the corresponding rim, the long part of the hubs of one set all being on the same side of their corresponding rims and the long part of the hubs of the other set all being on the opposite side of their corresponding rims, the hubs of each set separating their rims by spaces, and means supporting said shafts so that the rims of each set enter the spaces between the rims of the other set.

OSCAR V. PAYNE.
